CHAIR

John Gawrys, Belleville, Mich.
(8555 Massery Lane, Santee, Calif. 92071)

Filed Feb. 5, 1968, Ser. No. 10,424

Term of patent 14 years

Int. Cl. D6—01

U.S. Cl. D15—1

FIG. 1 is a front perspective view of a chair embodying my new design;

FIG. 2 is a side perspective view thereof;

FIG. 3 is a side view thereof; and

FIG. 4 is an elevational sectional view taken along the lines 4—4 in FIG. 1.

I claim:

The ornamental design for a chair, as shown.
